UNITED STATES PATENT OFFICE

158,218

HANDBAG FRAME

Max H. Randolph, New York, N. Y.

Application January 7, 1950, Serial No. 7,060

Term of patent 7 years

(Cl. D87—2)

To all whom it may concern:

Be it known that I, Max H. Randolph, a citizen of the United States, residing in the city, county, and State of New York, have invented a new, original, and ornamental Design for a Handbag Frame, of which the following is a specification, reference being had to the accompanying drawing, forming a part thereof, in which the figure is a perspective view of a handbag frame embodying my new design.

The opposite side of the frame has the same appearance as the side shown in the drawing.

I claim:

The ornamental design for a handbag frame, as shown and described.

MAX H. RANDOLPH.
